UNITED STATES PATENT OFFICE.

JOHN N. REYNOLDS, OF GREENWICH, CONNECTICUT, AND AMOS F. DIXON, OF NEWARK, NEW JERSEY, ASSIGNEES TO WESTERN ELECTRIC COMPANY, OF NEW YORK, N. Y., A CORPORATION OF ILLINOIS.

AUTOMATIC ELECTROMAGNETIC SWITCH.

1,076,149.

Specification of Letters Patent.

Patented Oct. 21, 1913.

Application filed October 5, 1910. Serial No. 585,425.

To all whom it may concern:

Be it known that we, JOHN N. REYNOLDS and AMOS F. DIXON, citizens of the United States, residing at Greenwich, in the county 5 of Fairfield and State of Connecticut, and Newark, in the county of Essex and State of New Jersey, respectively, have jointly invented a certain new and useful Improvement in Automatic Electromagnetic 10 Switches, of which the following is a full, clear, concise, and exact description.

This invention relates to automatic electromagnetic switches.

The object of the invention is to provide 15 a rotating switch, of the described character, having capacity to quickly and effectively connect and disconnect circuits or parts of circuits by a uniform step or advance movement and to do this when started into operation by current impulses which may vary widely in extent or duration.

A further object is to provide a simple, compact and inexpensive device, useful in connecting and disconnecting metallic 20 circuits.

The accompanying drawings illustrate the invention.

Figure 1 is a top plan view; Fig. 2 is an end elevation showing the magnet and the 30 circuit controlling wheel to be placed in the starting magnet circuit; Fig. 3 is a section on line 3—3, Fig. 1, showing the stop wheel and the pawl controlled by the magnet; Fig. 4 is a diagram of the controlling or 35 operating circuit; Fig. 5 shows the controlling magnet and its relation to the moving parts operated by it; and Fig. 6 is another view of the magnet and its relation to the clutch device.

40 The switch employs a metal plate *a*; a part thereof, *f*, is turned at an angle and again turned and shaped, as shown in Fig. 2, to form a support for the fixed spring contacts 10 which are held by angular metal 45 pieces 11 fixed to part *f* by screws 12. Metal piece 11 supports two contacts 10 insulated from each other and from part *f* by insulating material *i* all held together by screws 13. The plate *a* is turned up at 50 one end *e* to form a bearing for the end of the rotatable shaft *c*, and the other end of shaft *c* is supported in a bearing *b* fixed on plate *a*. On shaft *c* are a series of metal disks *o* with collars, fixed equidistant by

screws 20; each disk *o* is perforated with a 55 series of holes 14 (Fig. 3) near the periphery; to these disks *o* are fixed a series of segmental contacts 15; these contacts vary in angular extent designed to maintain an electrical contact for a greater or 60 lesser period during the rotation of shaft *c*, as may be required. The holes 14 are to provide for changing the position and sequence of the segments, to adapt the switch to any required conditions and to substitute 65 segments differing in extent. These segments are insulated from the disk which supports them as shown at 16, and are electrically connected to one another by the rivets or screws which pass through said 70 segments and through the holes 14 in the disks *o*; and two segments are fixed on opposite sides of each disk *o* respectively. The initial contact edge of each segment *o* is bent outward to engage the offset end 75 17 of a fixed contact 10; the contacts 10 engage the segments 15 on the flat side and make a rubbing contact therewith. These fixed and movable contacts, 10 and 15, are arranged to engage on successive disks *o* in 80 any desired sequence or radial positions and this arrangement may be changed at pleasure. The contacts 10 are pressed toward each other between parallel segments 15 during contact.

85 The shaft *c* is rotated by a power driven shaft *s*, and connection between the two shafts is controlled by a magnet *m*. This magnet is arranged to be energized by an initial electric impulse, which impulse may 90 be extremely light or short, or may be stronger or longer according to the degree of care exercised by the human agency transmitting the impulse. It is desirable that whatever the character of this transmitted 95 impulse, the switch shall advance a step or fixed unit distance and then stop unless the circuit be held closed or again closed at the end of such step. On the shaft *c* is fixed a flexible disk *d*; it is preferably made of 100 leather or some soft surfaced, yielding, resilient and self-sustaining material. Fixed on shaft *s* is a metal disk *v* in close proximity to the plane of rotation of disk *d*. Magnet *m* is on an extension of plate *a* and its 105 armature 25 is on an angular frame 21, which frame is pivoted at 31 between parallel angular plates 23, and plates 23 are held

10 plate *a* by a screw 24. The armature frame 21 carries a pawl 26, and said frame 21 and pawl 26 are retracted by spring 22. The pawl 26 is in position to engage a ratchet or stop wheel 27 fixed on shaft *c*; this ratchet wheel 27 is formed of a metal disk having its periphery cut at intervals forming a series of separate projections 28, like teeth, the advance edge 29 of each such projection 28 being curved or turned to allow the pawl 26 to engage the edge of the next projection in the plane of the disk; between these notches the pawl 26 rides on the surface of a projection 28. Between the 15 parallel plates of the armature frame 21 is an arm 30 composed of two parallel members pivoted at 31; the free end of arm 30 carries a freely rotatable disk *w* and arm 30 is connected to armature frame 21, and held 20 in a retracted position, by a spring 32. The movement of the arm 30 by the spring 32 is limited by a pin 33 passing through the armature frame 21, as shown in Figs. 1, 3, 5 and 6. It is apparent, therefore, that the 25 arm 30 carrying the disk 25, is pivoted in the armature frame 21 and is yieldingly held in a certain position by the spring 32; and that the armature frame 21 is itself pivotally supported and yieldingly held in a 30 certain position by the spring 22. When magnet *m* is energized, disk *w* is carried into engagement with the leather disk *d* and disk *d* is deflected and forced into engagement with disk *v* on driving shaft *s* so that disk *d* and shaft *c* are rotated during the 35 time these disks *d*, *v* and *w* are in the last described contact relation.

Fig. 4 diagrammatically illustrates the actuating mechanism of the device above 40 described, and shows the electrical circuits which control it. The parts *c*, *m*, *w*, *v*, *d*, *s*, 21, 22, 26, 27, 30 and 32 will be recognized as diagrammatically representing the parts which are given these reference characters 45 in the other figures. Only one rotary contact member is shown on the shaft *c*, and for the sake of clearness this contact disk 39 and its coöperating contact finger 40 are of simpler construction than the contact segments 50 50 and the coöperating fingers 10 hereinbefore described. With the arrangement shown in Fig. 4 it is to be understood that the finger 40 engages and makes electrical connection with the disk 39 only when said 55 finger is riding upon the outer ends of the projections 41 on the edge of the disk 39; it being understood that the same result might be accomplished by the construction hereinbefore described.

60 The operation of the switch mechanism is controlled by a circuit closer *p* located in the circuit through the actuating coil 43 of a relay having a movable contact member 44 which coöperates with the fixed contact member 45. The current for the magnet *m*

is furnished by a battery 46. From this battery current is carried to the magnet *m* through two circuits, that is, either through the contacts 44 and 45 of the relay and the wire 47, or through the wire 48, the disk 39, contact finger 40 and wire 49, as it will be obvious from Fig. 4.

The operation of the system shown in Fig. 4 is as follows: When the switch *p* is closed, the actuating coil 43 of the relay is energized and the contacts 44 and 45 of said relay are brought together. The magnet *m* is therefore energized from the battery through the contacts of the relay and through the wire 47. The energization of magnet *m* causes movement of the armature 21 with consequent release of the disk 27 by the arm 26 and driving of the shaft *c* from the driving shaft *s*, in the manner hereinbefore described. The first slight rotation of the shaft *c* causes one of the projections 41 on the disk 39 to engage with the finger 40 with the result that a connection from the magnet *m* to the battery 46 is completed through the wire 49, finger 40, disk 39 and wire 48. This circuit is independent of the circuit through the contacts 44 and 45 of the relay, and even if the switch *p* is open, the magnet *m* will continue to be energized and the shaft *c* will continue to be driven until the finger 40 ceases to engage with the projection 41, thereby interrupting the circuit. The projections 41 on the disk 39 are so arranged that the duration of contact between the finger 40 and the projections will be sufficient to insure rotation of the shaft *c* only through one complete step in the rotation of the shaft *c*. From the foregoing it will be obvious that even if the switch *p* is only maintained closed momentarily, rotation of the shaft *c* will take place through an angle corresponding to a complete step.

What we claim and desire to secure by Letters Patent is:

1. In an electromagnetic switch, the combination of a rotatable shaft, disks on said shaft suitably spaced and fixed in position, segmental contacts arranged at varying circumferential points on said disks, each said contact having its advance edge curved away from its complementary contact, and a series of fixed complementary contacts, one for each segment, each such contact having its engaging terminal offset to engage a segmental contact on the surface thereof.

2. In an electromagnetic switch, the combination of a rotatable shaft, a series of pairs of fixed flat spring contacts, and a series of pairs of segmental contacts fixed on said shaft, each pair in position to engage a pair of said fixed contacts between them and to deflect them, substantially as described.

3. In an electromagnetic switch, the combination of a rotatable shaft, a series of

disks fixed on said shaft, segmental contacts adjustably fixed to said disks at varying circumferential points, and suitable complementary flat spring contacts arranged to engage said contacts on the flat surface thereof.

4. In an electromagnetic switch, a rotatable shaft, disks fixed thereto, said disks having perforations at suitable points adjacent to the circumference thereof, a series of fixed contacts, a series of complementary segmental contacts, and means entering said perforations for adjustably securing said segmental contacts to said disks.

5. In an electromagnetic switch, a rotatable shaft, a series of disks thereon, segmental contacts insulatively secured to said disks, and stationary spring contacts arranged to engage said segmental contacts upon rotation of said shaft.

6. In an electromagnetic switch, a rotatable shaft, disks fixed thereto, insulated segmental contacts adjustably secured to said disks, and corresponding fixed contacts

arranged to engage said segmental contacts 25 upon rotation of said shaft.

7. In an electromagnetic switch, a rotatable shaft, a disk thereon, a pair of electrically connected cam shaped contacts insulatively secured on opposite sides of said disk, and fixed brushes arranged to engage said contacts upon rotation of said shaft.

8. In an electromagnetic switch, a rotatable shaft, disks thereon, pairs of electrically connected cam shaped contacts insulatively secured to opposite sides of said disks respectively, and corresponding pairs of fixed brushes arranged to engage adjacent sides of said contacts upon rotation of 35 said shaft.

In witness whereof, we, hereunto subscribe our names this 30th day of September 40 A. D., 1910.

JOHN N. REYNOLDS.
AMOS F. DIXON.
